UNITED STATES PATENT OFFICE.

EDWARD G. LEHMAN, OF CANTON, OHIO, ASSIGNOR, BY MESNE ASSIGNMENTS, TO
UNITED ALLOY STEEL CORPORATION, OF CANTON, OHIO, A CORPORATION OF
NEW YORK.

SAFE CONSTRUCTION.

Application filed January 24, 1921. Serial No. 439,633.

To all whom it may concern:

Be it known that I, EDWARD G. LEHMAN, a citizen of the United States, residing at Canton, in the county of Stark and State of Ohio, have invented certain new and useful Improvements in Safe Construction, of which the following is a specification.

This invention relates to the construction of a fireproof safe or cabinet adapted to 10 withstand high temperatures and to prevent a breaking or crushing of the walls by impact with other bodies.

Safes of this character must be so constructed that high temperatures may be resisted for a considerable time without resulting in any material damage to the safe or its contents, and the structure must also possess sufficient strength to prevent buckling or bending by the blows of other 20 bodies in the wreckage of a burning building.

Safes of this type are of comparatively light weight as distinguished from the usual burglar proof safes, and usually comprise 25 spaced inner and outer shells between which is located suitable heat insulating material. In such a light weight safe or cabinet it is difficult to secure sufficient strength in the shell to protect the heat insulating material 30 from becoming crushed or broken without increasing the weight of the safe to such an extent as to make it too cumbersome for practical purposes.

It is well understood that the juncture of 35 the side walls with the top, bottom, front and rear walls offers the least resistance to heat and in order to overcome this weak point as well as to provide an impact resistance sufficient to prevent serious damage 40 to the insulating material in case the safe falls or is struck by falling bodies, the present structure has been designed.

The objects of the invention are attained 45 by providing a safe construction comprising an interior shell and an outer shell spaced therefrom, with transversely corrugated concaved walls located around the inner shell and the entire space between the concaved walls and the outer shell being filled with 50 heat insulating material forming arches on all sides of the safe, thus making a structure which is not readily distorted by heavy blows, even though the outer shell be heated to a high temperature, and the increased 55 thickness of the insulation at the angles and

corners, gives a greater heat resistance at the most exposed places.

In the drawings, forming part hereof;

Figure 1 is a transverse vertical section of a safe embodying the invention;

Fig. 2, a section on the line 2—2, Fig. 1, and

Fig. 3, a section on the line 3—3, Figs. 1 and 2.

Similar numerals refer to similar parts throughout the drawings.

The outer shell of the cabinet comprises the outer side walls 1—1, the rear wall 2, the top wall 3 and the bottom wall 4. The side walls may be connected to the rear 70 walls by overlapping the adjacent edges of the side and rear walls and forming seams 5, the rear wall being connected to the top wall by a similar seam 6. The top wall may be formed of two halves, each integral with the 75 adjacent side wall, the abutting edges thereof being bent back upon themselves as shown at 7 and connected by means of a channel strip 8. The rear wall may be connected to the bottom wall by means of a seam 9 and the 80 side walls are preferably extended below the bottom wall and provided with the inwardly disposed channel portions 10 which receive the down turned flanges 11 of the bottom wall. The usual rollers 12 may be 85 provided for easily moving the safe.

The inner shell comprises the side walls 13—13, the rear wall 14 and the top and bottom walls 15 and 16 respectively, said inner walls being preferably provided at 90 their edges with angular flanges 17 which are overlapped and connected together in any suitable manner, the inner shell being spaced from the outer shell upon all sides.

Transversely corrugated concaved sheets 95 18 are provided around the side, rear, top and bottom walls of the inner shell being preferably provided at their edges with the overlapping angular flat flanges 19 which may be connected in any convenient manner 100 to the inner shell.

The entire space between the concaved walls 18 and the outer shell is filled with suitable heat insulating material 20, thus forming an arch upon each side of the safe, 105 and thickest portions of the arches being located at the angles and corners of the safe where the greatest heat resistance is necessary, and the air spaces 21 between the concave sheets and the walls of the inner shell, 110

not only supplements resistance of the heat insulating material, but delocalizes such heat as may penetrate the same and distributes and dissipates its intensity throughout the 5 corresponding wall of the inner shell.

Each door 22 is formed of a hollow steel shell 22^a entirely filled with heat insulating material 23, said doors being hingedly connected in the usual manner to the body portion of the safe as indicated at 24.

I claim:—

1. A heat resisting safe or cabinet comprising spaced inner and outer metal shell walls, and heat insulating material located 15 between said shells, the heat insulating material being arched from the inner shell walls.

2. A heat resisting safe or cabinet comprising spaced inner and outer shells, and

heat insulating material located between 20 said shells, the thickness of the heat insulating material in the side of the case gradually decreasing from the angles and corners to the middle thereof.

3. A heat resisting safe or cabinet comprising inner and outer metal shell walls, intervening metal sheets concaved from the angles of the inner shell walls, and heat insulating material filling the space between the outer shell and the concaved sheets. 30

4. A heat resisting safe or cabinet comprising spaced outer and inner metal shell walls, transversely corrugated metal sheets concaved from the angles of the inner shell of the walls, and heat insulating material 35 filling the space between the outer shell and the concaved sheets.

EDWARD G. LEHMAN.
